LAUNDRY TRAY

John Maurus, 16100 Kennedy, Roseville, Mich. 48066

Filed Mar. 29, 1965, Ser. No. 84,465

Term of patent 14 years

(Cl. D4—3)

Fig.4Fig.6Fig.5Fig.7Fig.8

FIG. 1 is a perspective view of a laundry tray embodying my design;

FIGS. 2 and 3 are top and bottom plan views thereof;

FIGS. 4-7 are horizontal sectional views of the structure shown in FIGS. 1 and 2 taken, respectively, on the lines 4-4, 5-5, 6-6 and 7-7 thereof; and

FIG. 8 is a perspective view of said tray shown in association with certain articles it is designed to hold and with a laundry tub on which it mounts; the tub and articles being shown for illustrative purposes.

I claim:

The ornamental design for a laundry tray, as shown and described.
